UNITED STATES PATENT OFFICE.

HOWARD O. BRIGGS, OF MINNEAPOLIS, MINNESOTA.

CORD HOLDER FOR VACUUM CLEANERS, LAMPS, AND THE LIKE.

Application filed April 9, 1925. Serial No. 21,889.

My invention relates to cord holders for the handles of vacuum cleaners and the like.

The flexible connectors with which 5 vacuum cleaners are equipped are provided with a plug. Usually the handle has spaced holders thereon, about which the flexible cord connectors are wound or coiled, the plug end being intertwined about one or 10 more of the coiled lengths of the cord, in order to prevent the cord from getting loose and falling off from the holders. However, 15 this and other expedients have, so far as I know, failed to securely hold the cord in position.

Now then, it is one of the important features of this invention to provide an automatic take up reel which may be supported on the handle which, when released, will 20 wind up the cord to an out of the way position.

This reel is also useful in connection with the flexible connectors of lamps, such as trouble lights and the like. The structure 25 of the reel is substantially simple, strong, durable, efficient and reliable, inexpensive to construct and install, and otherwise well adapted to the purpose for which it is designed.

With the above and numerous other objects in view, as will appear as the description proceeds, the invention resides in certain novel features of construction, and in the combination and arrangement of parts 35 as will be hereinafter more fully described and claimed.

In the drawing:

Figure 1 is an end elevation of the automatic take up reel, showing the same mounted on a handle of a vacuum cleaner or the like.

Figure 2 is an elevation thereof, taken at right angles to that shown in Figure 1 and showing one end in section.

Referring to the drawing in detail, it will be seen that 1 designates the handle of a vacuum cleaner or the like, 2 hollow brackets attached to the handle 1 and extending in parallel spaced relation therefrom. A cylindrical casing 3 is mounted between these

hollow brackets 2. A rod 4 extends longitudinally through the casing 3 and also through the hollow brackets 2 and has one end headed and countersunk in one bracket 2 as at 5 and the other end engaged with 55 a nut 6 in the other bracket. Cylindrical blocks 7 are mounted near the ends of the rod 4 within the casing 3. A hollow reel or cylinder 8 is rotatable over these cylindrical blocks 7 and is normally held in a 60 predetermined position by a coil spring 9 disposed about the rod 4 and having one end fixed to this rod and the other end fixed to the reel. A pair of discs 10 are formed on the ends of the reel 8, one at each end 65 thereof. One of the discs is provided with recesses 11 having at their edges an annular series of teeth 12, engageable with a pin 13, 70 slideable through one of the brackets 2 and through the side of the casing adjacent thereto. This pin is spring pressed inwardly, as at 14. A conductor disc or ring 15 is mounted in the casing 3, on each end thereof. These rings 15 are insulated from the casing, as at 16, and conductors 17 are attached thereto and are led through the hollow brackets 2. A pair of housings, one at 75 each end, are provided, on the reel 8, as at 18, and have slideable therein, spring pressed wipers 19, which are adapted to engage the 80 conductor rings 15. Conductors 20 are attached to the wipers 19 and pass through a loop 21 provided on the intermediate portion of the reel. These conductors 20 are normally wound about the reel, so that when 85 they are pulled or unwound from the reel, the spring 9 is tensioned, so that if the pin 13 is pulled outwardly, the reel will automatically take up these cords.

It is thought that the construction, operation and advantages of this invention will be clearly understood, without a more detailed description thereof. It is desired, however, to point out that numerous changes in the details of construction, and in the 90 combination and arrangement of parts may be resorted to, without departing from the spirit or scope of the invention as herein-after claimed or sacrificing any of its advantages.

Having thus described my invention, what I claim as new is:

A take up reel of the class described, including a casing, a reel rotatable in the casing, rings mounted in the casing concentrically in respect to the axis of the reel, and one at each end thereof, a pair of housings on the reel one at each end thereof,

spring pressed wipers slidably mounted in the housings to engage the rings, wires engaged with the wipers, and a loop on the central portion of the reel through which the wires pass. 10

In testimony whereof I affix my signature.

HOWARD O. BRIGGS.
